US0D1036049S

(12) **United States Design Patent** (10) **Patent No.:** **US D1,036,049 S**
(45) **Date of Patent:** **** Jul. 16, 2024**

(54) **CONVEYOR BELT MODULE**

(71) Applicant: **Laitram, L.L.C.**, Harahan, LA (US)

(72) Inventor: **Gilbert J. MacLachlan**, Harahan, LA (US)

(73) Assignee: **Laitram, L.L.C.**, Harahan, LA (US)

(**) Term: **15 Years**

(21) Appl. No.: **29/785,846**

(22) Filed: **May 27, 2021**

(51) **LOC (14) Cl.** **12-05**

(52) **U.S. Cl.**

USPC **D34/29**

(58) **Field of Classification Search**

USPC **D34/29**

CPC **B65G 17/10; B65G 17/30; B65G 17/46**

See application file for complete search history.

(74) *Attorney, Agent, or Firm* — Catherine M. Bishop

(57) **CLAIM**

The ornamental design for a conveyor belt module, as shown and described.

DESCRIPTION

FIG. 1 is an isometric top view of a conveyor belt module according to the present invention.

FIG. 2 is an isometric bottom view of the conveyor belt module of FIG. 1.

FIG. 3 is a top view of the conveyor belt module of FIG. 1; and,

FIG. 4 is a bottom view of the conveyor belt module of FIG. 1.

The broken lines in the figures are to show portions of the conveyor belt module which are not part of the claimed design.

1 Claim, 3 Drawing Sheets
